UNITED STATES PATENT OFFICE.

JAMES V. BOYETT AND THOMAS E. BOYETT, OF MOBILE, ALABAMA.

AUTOMATIC CENTRIFUGAL STARTER-LOCK FOR AUTOMOBILE-ENGINES.

1,264,766.

Specification of Letters Patent. Patented Apr. 30, 1918.

Original application filed December 28, 1916, Serial No. 139,339. Divided and this application filed June 2, 1917. Serial No. 172,553.

To all whom it may concern:

Be it known that we, JAMES V. BOYETT and THOMAS E. BOYETT, citizens of the United States, and residents of Mobile, in 5 the county of Mobile and State of Alabama, have invented a certain new and useful Improvement in Automatic Centrifugal Starter-Locks for Automobile-Engines, of which the following is a specification.

10 This application is a division of our application, Serial Number 139,339, filed December 28, 1916, for automatic safety starter locks for automobile engines.

The principal object of our present invention is to provide an improved speed responsive or centrifugal device operable from one of the driven shafts of an automobile engine for rendering impossible the coupling of the starter motor and the engine 20 motor while the latter is running.

With these and other objects in view which will become apparent as the description proceeds, the invention resides in the construction, combination, and arrangement 25 of parts hereinafter more fully described and claimed and illustrated in the accompanying drawings, in which like characters of reference indicate like parts throughout the several figures, of which:

30 Figure 1 is a perspective view of a speed responsive lock constructed in accordance with the invention, showing the same mounted upon an automobile engine;

Fig. 2 is a similar view showing the position of the parts when the engine is running;

Fig. 3 is a section through the speed responsive device.

Referring more particularly to the drawing, the automobile engine is indicated generally at 5, and at 6 is represented one of the driven shafts of the engine, on which the speed responsive device is mounted. The starting motor, which may be of any 45 suitable type, is not shown, but the pedal for controlling the starting motor is indicated at 7. This pedal is pivotally mounted in the usual manner, and is adapted to be depressed by the foot of the driver when the starting motor is to be thrown into operation for turning the engine over in starting the latter.

50 Depression of the pedal 7 is adapted to be controlled by a latch 8 in the form of an elbow lever, pivotally mounted in co-

operative relation to the pedal 7, and one arm of this latch is provided with a shoulder 9 adapted, when the latch is moved into operative position, to form a stop to prevent the depression of the pedal.

60 The speed responsive device includes a ring or collar 11, keyed or otherwise suitably fixed on the shaft 6, said collar being provided with a plurality of pivoted governor arms 12 provided at their outer ends with weights 13 and having their inner ends 14 arranged in the path of movement of a sleeve 15, said sleeve being loosely mounted on the shaft 6 and movable axially of the latter. Interposed between the collar 11 70 and the sleeve 15 is a coiled spring 16 which tends to hold the sleeve in the position indicated in Fig. 3, whereby the governor arms will be held inwardly relatively of the collar.

75 The sleeve is equipped with an annular groove 17 in which the forked upper end of an arm 18 plays. Through the lower end of the arm 18 extends one end of a rod 19, the rod being fixed with relation 80 to the arm through the medium of jam nuts 20. The other end of the rod 19 is connected to the other arm of the latch 8 as shown in Fig. 2.

85 The operation of the device may be briefly described as follows: While the engine is at a standstill, the sleeve 15, being pressed outwardly by the spring 16, retains the governor arm in the position indicated in Fig. 3. The latch 8, through the connecting rod 90 19 and arm 18, will be held in the inoperative position indicated by full lines in Fig. 2. The starter pedal 7 will thus be in an unlocked position, and may be depressed whereby to couple up the starter motor with the engine in order to start the latter. As soon as the engine attains a predetermined speed, the rotation of shaft 6 and with it the collar 11, will cause the governor arms to swing outwardly, thus, through the pressure of the inner end 14 of the arms against the sleeve 15, shifting the latter inwardly against the tension of the spring 16, and hence moving the rod 19 in the direction indicated by the arrow in Fig. 2, whereby to 100 shift the latch 8 upwardly into operative position for preventing depression of the pedal 7, as indicated by the dotted lines in Fig. 2. Hence, as long as the engine rotates at or above the predetermined speed, it will 110

be impossible to depress the pedal 7, and thus there will be no danger of the starter motor and engine being coupled together.

While we have set out the preferred embodiment of this type of starter lock, we may desire to make such changes in the construction, combination, and arrangement of parts thereof as do not depart from the spirit of the invention and the scope of 10 the appended claims.

We claim:

1. In combination, a starter member, a latch to prevent rotation of the starter member, a rotary collar, weighted arms mounted 15 on the rotary collar, a sleeve axially slideable within the collar, a spring housed by the collar and normally pressing the sleeve outwardly, and connecting means between the latch and sleeve to throw the latch into the 20 path of the starter member and prevent

operation thereof when the rotary collar attains a given speed.

2. In combination, a shaft, a collar rotatable with the shaft, a sleeve loose on the shaft and having an offset portion slideable 25 within the collar, a spring housed by the collar and exerting an outward pressure on the sleeve, weighted arms pivoted to the collar and in co-operative relation with the sleeve, a starter member, a latch, and connecting means between the sleeve and latch for throwing the latter into the path of the starter member to prevent operation thereof when the said shaft attains a given speed. 30

JAMES V. BOYETT,
THOMAS E. BOYETT.
